REVERSING-SWITCH FOR ELEVATOR-MOTORS.

1,252,739.

Specification of Letters Patent.

Patented Jan. 8, 1918.

Application filed November 1, 1915. Serial No. 59,144.

To all whom it may concern:

Be it known that we, JOHN E. THOMPSON and CLARENCE W. JAMESON, citizens of the United States of America, and residents of Chicago, Cook county, Illinois, have invented a certain new and useful Improvement in Reversing-Switches for Elevator-Motors, of which the following is a specification.

10 Our invention relates to electrical switches and has more particular reference to improvements in switches for controlling the circuits of electric motors, such as elevator motors and the like.

15 One of the objects of our invention is to provide an improved reversing or controlling switch of this character which will be simple, durable and reliable in construction and effective and efficient in operation.

20 Other objects of our invention will appear hereinafter.

Our invention consists in the features of novelty exemplified in the construction, combination and arrangement of parts herein-

25 after described, shown in the accompanying drawings and more particularly pointed out in the appended claims.

Referring to the accompanying drawings:

30 Figure 1 is a view in front elevation of a switch structure embodying our invention.

Fig. 2 is a view in elevation of the reverse side or face of the structure shown in Fig. 1.

Fig. 3 is a section substantially on the line 3—3 of Fig. 1.

35 Fig. 4 is a section substantially on the line 4—4 of Fig. 1.

Fig. 5 is a detail section on the line 5—5 of Fig. 1.

The structure which we have shown in the 40 drawings, and which embodies our invention, is designed more particularly for use in connection with the operation of elevators and its purpose in this connection is to control the circuits of the electric elevator

45 motors by reversing the current and connections as desired to run the elevator in either direction. In this particular structure the operating parts are mounted upon a panel or plate A of slate or suitable material, this panel being supported in upright 50 position on a frame B consisting of the uprights B¹ and horizontal base member B² having feet B³. On this panel A is a plu-

rality of main switches C and smaller

switches D by which the circuits of the 55 motor are controlled. In this structure there are two main switches C on each side of the panel, arranged to operate toward and from the face thereof. Each switch is made in two arms or sections 1 and 2, the section 2 60 being pivoted at 3 on the other section 1 so as to permit of a relative movement of the sections. The section or arm 2 normally lies flat against the arm or section 1 but can swing outwardly away from said arm 1. 65 The arm 1 is pivoted near its lower end to a supporting bracket 5. Its lower end however extends below the pivotal point and between said lower end and the lower end of arm or section 2 is a yielding connection. This is in the form of a spiral spring 8, which is positioned on a bolt 9 between an adjustable nut 10 on the bolt, and the arm 2. The bolt is fastened to the end of the arm or section 1 and extends through an opening 70 in the arm 2. This spring thus tends to yieldingly maintain the arms or sections of the switch in their closed or normal relation. The upper ends of the switch arms or sections 1 carry contact members 11, which, in the present structure, are in the form of cylindrically shaped blocks of carbon or other suitable material. These contact members may be fastened in any manner desired to the ends of the arms, but in this structure 75 the arms are provided with concave or yoke-shaped portions forming seats for the contact members 11. The contact members are clamped or fastened in their seats by bolts 12 which extend through the members 11 and are screwed into the upper ends of the arms. These bolts carry at their upper ends small curved clamping members 13 which embrace a portion of the carbon blocks. 80 This construction makes it possible to conveniently renew the contact members or blocks 11 without disassembling the switch structure. The contacts 11 of the main switches coöperate or contact with similarly shaped carbon blocks 14 when the switches are swung toward the panel. These fixed contact members 14 are abutted against the supporting panel and they are supported in fixed brackets or members 15 in the manner similar to the carbon blocks 11. In this 85 structure the fixed contacts 14 of the main switches on both sides of the supporting panel are preferably positioned in axial 90 95 100 105

alinement, and their supporting brackets 15 are held in place by common bolts 16 which pass through the supporting panel. The supporting brackets have extensions 17 5 which lie flat against the panel and which preferably terminate adjacent the upper edge of the supporting panel. The ends of the extensions 17 on opposite sides of the panel are fastened by the single bolt 18, and 10 these bolts form terminals to which conductors may be connected. In this manner two terminals are formed at the upper edge of the panel, and each terminal is common to corresponding fixed contacts 14 on opposite 15 sides of the panel. The circuit, being closed and opened at the abutting ends of the fixed contact 14 and their respective corresponding contacts 11 on the switches, renders these contact members subject to considerable arcing especially when the circuit is broken. 20 But in order to eliminate and render ineffective the arcing which occurred at these points we provide suitable magnetic blow-out devices. These blow-out magnets 20 are 25 positioned preferably above the edge of the supporting panel and each magnet 20 is common to the two corresponding switches on opposite sides of the panel. The pole pieces 21 of these magnets, as shown in the drawings, are positioned at the end of and support said magnets. They are U-shaped in structure so as to straddle the upper edge of the panel to which they are fastened by the bolts or screws 22. The lower ends 23 of 30 these pole pieces are extended laterally so as to bring them into proper relation to the contact areas of the switches, and their faces 24 are curved to conform substantially to the curvature of the cylindrical contact 35 pieces. They are thus arranged so as to maintain a field of magnetic flux across the gap when the switches are closed or opened and thus effectually "blow-out" or eliminate the arcs which otherwise are likely to 40 occur and damage the contact. Between the main switches on one side of the panel we provide a plurality of smaller switches D which, as hereinafter explained, control the circuits for the shunt winding of the motor 45 and the circuit of the accelerator solenoid. These switches are preferably constructed in identically the same manner as the larger switches just described and need no further description as to structure. Switches of the 50 character to which our invention relates are especially, though not necessarily, adapted to the control of elevator motors, and they are arranged to reverse the circuit in such manner as to change the direction of travel 55 of the elevator. These switches are usually located adjacent the elevator shaft and are actuated by controlling members or wheels in the car through the medium of cables. Between the groups of switches on each side 60 of the supporting panel we provide an oper-

ating shaft 25 supporting in bearings in the frame and having a plurality of cams arranged to operate the switches when the shaft is rotated. This shaft is connected by cables or other suitable mechanism (not 70 shown) so that it may be rotated in either direction by the controlling levers in the car corresponding to the direction of travel of the car. Each pair of main switches (and by pair in the present structure we refer to 75 the correspondingly opposite switches on opposite sides of the supporting panel) has associated with it a common operating cam 26. This cam being positioned between the lower ends of the switches below their 80 pivotal points and keyed to the shaft so as to be rotated thereby. The lower ends of the sections or arms 2 of each switch of the pairs have anti-friction rollers 27 which in this structure lie in the plane of its respective cam and which rides on the periphery thereof. These cams are so arranged that when the shaft is rotated in either direction they will exert the lateral thrust on the lower ends of the arms 2 of the switches and 85 swing or close said switches about their pivotal points into engagement with the fixed contacts 14, as shown in dotted lines in Fig. 4, the switches on either side of the panel being actuated in accordance with the 90 direction of rotation of the cam. The arms 1 and their contacts 11 of the switches reach closed position before the rollers have reached the peaks of the cams and in consequence continued rotation of the cams will 95 100 swing the sections 2 about their pivots and against the resistance of the spiral springs 8, thus holding the switches in yielding engagement with their fastened contacts. After the switches have been closed, however, 105 and the rollers have reached the peaks of the cams further rotation of the cam will have no particular effect on the switches except to yieldingly hold them in closed position, but it will be observed that the rotation of the shaft in either direction is unrestricted. Thus these switches embodying 110 our invention can be adapted to various types and styles of elevators in which the throw of the controlling levers vary. For instance the throw or extent of movement of the controlling levers in an elevator might have been designed for the control of some other type of reversing switch, and might be greater than that required for a switch of 115 our invention. It will be observed, however, that our improved structure is adapted to such controlling lever because although the throw of the lever might be greater than that required to close the switch of our 120 structure, the unrestricted rotation of which the shaft is capable will not have the effect of interfering with the throw or extent of movement of said controlling lever. The smaller switches D, on one side of the panel 125 130

as we have before mentioned, are adapted in this particular structure to control the circuit of the motor shunt winding and the solenoid of an accelerator. These circuits, 5 and particularly the shunt winding of the motor, should, of course, be closed before the armature circuit is closed and should be opened or broken after the armature circuit is opened. And we provide cams 30 on the 10 operating shaft 25 for actuating the smaller switches D in the same manner as the cams of the larger switches. These cams, however, are arranged so that the small switches D will be closed in either direction of rotation of the shaft; that is when either the 15 main switches C on one side of the panel or those on the other side are closed. We furthermore proportion the cams 30 and so time them that they will close the small switches D an instant before the main switches are 20 closed and will accordingly allow them to open an instant or so after the main switch is open, so that the motor shunt winding circuit will be closed before and will remain 25 closed for a period after the closure and opening of the main switches. In order to guard against any possibility of the main 30 switches on one side of the panel sticking or failing to open when the switches on the other side thereof are closed we provide an interlocking or safety arrangement which in the present construction consists of rods or members 35 extending loosely through openings in the panels. These rods are positioned between and substantially in the 35 plane of the switches of each pair and one of their ends is pivotally connected as at 36 to one of the switches of the pairs and their other ends are arranged to abut 40 against the other switch of the pairs on the opposite side of the panel. These rods or members are long enough so that when the main switches on one side of the board or panel are being closed the rods will force 45 the switches on the opposite side of the panel away from their contacts before the first mentioned switches are positively closed. This arrangement provides against 50 the switches or any of them on both sides of 55 the boards being in closed position simultaneously, even though any of said switches should stick or otherwise fail to open. Of course in the ordinary operation of the structure the switches are considerably 60 heavier above their pivotal points and return to open position by the action of gravity when the operating cam is rotated sufficiently to permit them to return. The supporting brackets 5, in which the switches are 65 pivotally mounted, and which we have before mentioned, are mounted on the insulating panel by suitable bolts. In order to avoid the current passing through the hinge or pivotal connections of the switch a flexible cable or conductor 70 is used, one end

of which is fastened to the switch arm 1 and the other end to the bracket 5. The brackets 5 have extensions or ears 37 preferably integrally formed therewith but disposed at one side thereof considerably to one side of 70 the plane in which the switches of a pair are mounted, and these extensions or ears 37 are secured to the panel by bolts 38 and 39, thus firmly holding the brackets in position. These extensions 37 serve as conductors for 75 the current and the upper bolts 39 may also be arranged to serve as binding posts to which conductors may be connected. By disposing the ears or extensions 37 in this manner we are enabled to mount the 80 switches of the pair in the same plane and still provide a firm mounting for the brackets and terminals for each individual switch, suitably insulated by means of the supporting 85 panel from all other switches.

It is obvious that any suitable circuit arrangement may be provided in which our improved reversing switch may be utilized. In the drawings, and particularly in Fig. 2, we have shown our improved switch as being connected in a manner to control the 90 circuits of a compound wound motor E, the armature, shunt winding and compound winding of which are represented diagrammatically by the reference letters F, G and 95 H, respectively. This reversing switch is also shown as being connected and operable in conjunction with an accelerator represented diagrammatically at J and of the type which constitutes the subject matter of our 100 co-pending application, Serial No. 54,625, filed October 7, 1915. This accelerator is adapted to gradually cut out or decrease the amount of resistance R in the motor circuit for the purpose of governing the speed of 105 the motor in the well known way. It has a plurality of pairs of contacts K, each pair of which are bridged by a suitable switch, as described in our co-pending application above mentioned. This accelerator also has 110 an operating solenoid L for successively closing the switches which bridge the contacts K. A suitable source of current is represented by the line conductors 40 and 41. The line conductor 41 is connected to 115 one of the common terminals 18 connected with the fixed contacts of the main switches. The other line conductor 40 extends to and is connected to a binding post 42 of the accelerator K. The other terminal 18 is connected by the conductor 43 to one terminal of the compound winding H to the motor, the other terminal of which is connected by conductor 44 to a binding post 95 of the accelerator, so as to include the compound 120 winding H of the motor in series with the motor armature circuit while there is any resistance left in the circuit when the accelerator bridges its last pair of contacts K. The compound winding of a motor is 125 130

short circuited. One terminal of the motor armature F is connected by conductor 46 to a binding post 47 on the upper corner of the panel, and the other terminal of the 5 armature is connected by a conductor 47 to another binding post 48 on the panel. The binding post 47 is connected with a conductor 49 which leads to the terminal 39 of one of the main switches C on one side 10 of the board. And this terminal 39 is also connected by a conductor 50 to the terminal 39 of a switch C on the opposite side of the panel. In like manner binding post 48 is connected by conductor 51 to the terminal 15 39 of a switch C on the first mentioned side of the board. The terminal 39 is also connected by a conductor 52 to the terminal 39 of a switch C on the opposite side of the board. Thus it is obvious that when the 20 two switches C on one side of the panel A are closed the current will traverse the motor armature circuit in one direction and when these switches are open and the two switches on the opposite side of the panel 25 are closed the current will traverse the armature circuit in the opposite direction. In this manner the current traverses the armature circuit in either direction depending upon which set of switches are closed, 30 and the closure of these switches are, of course, controlled by the operator in the car, as hereinbefore explained. The bracket 5 in which the smaller switches D are pivotally mounted is common to both of these 35 switches and is fastened to the panel by means of the bolts 55 which serve as binding posts or terminals. These terminals are both connected by a conductor 56 to the bracket which serves the fixed contact for 40 one pair of the main switches D, and in this manner are connected directly to the line conductor 41. The binding post D' of the fixed contact of one of these smaller switches is connected by conductor 57 to one terminal 45 of the motor shunt winding G, the other terminal of which is connected by a conductor 58 to a binding post 59 of the accelerator. This binding post is connected by conductor 60 to the line 40 so that when 50 switch D is closed the shunt winding G of the motor will be bridged across the line in the usual way. The binding post D² of the fixed contact of the other switch D is connected by conductor 61 to a binding post 55 62 of the accelerator and to this binding post is connected one terminal of the accelerator operating solenoid L, the other terminal of which is connected by conductor 63 to the binding post 59, so that this 65 solenoid when its circuit is closed by the small switch D, is also bridged across the line. The two blow-out magnets 20 are connected in series by a conductor 64 which is connected to the binding posts 47 and 48 so that these blow-out magnets are likewise

bridged across the line. We have shown an ordinary knife switch 65 by which the apparatus may be connected with or disconnected from the source of power as desired.

It will be obvious to one skilled in the art, 70 after having obtained an understanding of our invention from the disclosures herein made, that our invention is capable of modification without departing from the scope and spirit of the invention. 75

What we claim as our invention is:

1. The combination of a supporting panel having fixed contacts on each side thereof, a plurality of pivoted switches arranged in pairs on opposite sides of said panel movable 80 toward and from said contacts, and a rotary cam mechanism positioned between the switches of the pairs for closing them against their respective contacts.

2. The combination of a supporting panel 85 having fixed contacts on each side thereof, a plurality of pivoted switches on each side of said panel, movable toward and from said contacts, cam mechanism for closing them against their respective contacts, and 90 means operable to move the switches on one side of said panel away from their contacts when the switches on the other side close against their contacts.

3. The combination of a supporting panel, 95 pivotally mounted switches disposed on each side of said panel, a cam shaft disposed between the switches, and cams on said shaft rotatable into engagement with the switches to close the switches on either but not both 100 sides of said panel, depending upon the direction of rotation of said cams.

4. The combination of a supporting panel, pivotally mounted switches disposed on each side of said panel, a cam shaft disposed between the switches, cams on said shaft operable to close the switches on either but not both sides of said panel, and rods extending through the panel and operable to force the switches on either side of said panel 110 open when the switches on the other side close.

5. In a reversing switch of the class described, the combination of a pair of movable switches, rotary cam mechanism positioned therebetween operable to close one 115 of said switches in one direction of rotation and the other switch in the opposite direction of rotation, and a rod carried by one of said switches and extending into the path of the other switch for opening one of said switches when the other is closed.

6. In a switch of the class described, the combination of a pair of oppositely disposed pivoted switch arms, a contact with which 125 said switch arms coöperate and by which the pivotal movement thereof is limited, a rotary cam positioned between said switches and operable to close one or the other thereof against its contact, and a rod positioned 130

- between said switches for forcing one of said switches from said contact by the movement of the other toward said contact.
7. In a switch of the class described, the combination of a pair of oppositely disposed pivoted switch arms, a contact with which said switch arms coöperate and by which the pivotal movement thereof is limited, and means operable by the closure of one of said switches for opening the other of said switches.
8. The combination of a supporting member, a plurality of pairs of switches mounted on said supporting member, the switches of each pair being disposed on opposite sides of said supporting member, contacts for each pair of switches common to the switches of the pair and conductors connecting a switch of one pair on one side of the supporting member with a switch of another pair on the opposite side of said supporting member, an actuating arm positioned between and common to the switches of each pair, and means for actuating simultaneously the several cams to operate all of the switches on the one or the other side of said supporting member.
9. The combination of a supporting panel, a switch disposed on each side of said panel and movable toward and from the panel in the same plane, brackets outstanding from the panel for pivotally supporting said switches in the same plane, extensions on said brackets offset laterally in opposite directions with respect to the plane of operation of said switches, and bolts for securing the extension of one of said brackets to the panel independently of the other brackets and its extension.
10. The combination of a vertically disposed supporting panel, fixed contacts disposed on opposite sides of said panel and in alinement, movable switches mounted on opposite sides of said panel and adapted to coöperate with said contacts, and a blow-out magnet common to both of said switches positioned adjacent said fixed contacts and having a pole-piece at each end of said magnet, each pole-piece being divided to extend to the gaps between each of said fixed contacts and their respective switches.
11. The combination of a vertically disposed supporting panel of insulating material, a plurality of switch arms pivotally mounted on each side of said panel, yieldable arms pivotally mounted on said switch arms, a cam shaft disposed substantially in the plane of said supporting panel, a plu-
- rality of cams on said shaft, each cam being common to corresponding switches on opposite sides of said panel and adapted when rotated to engage the yieldable arms of the switches and close said switches.
12. The combination of an upright supporting panel, a switch pivoted on each side of said panel and having a yielding extension, a rotary cam positioned between said extensions and operable to engage one extension or the other in accordance with its direction of rotation to actuate said switches, a fixed contact on each side of said panel adapted to be engaged by the switch, whereby to cause said extension to yield, and means for rotating said cam.
13. The combination of an upright supporting board, oppositely disposed switches pivotally mounted on opposite sides of said supporting board and comprising yieldably related sections, a contact on said supporting board for each switch adapted to be engaged by one of the sections of the switch, and a cam positioned between said switches and arranged to engage the other section of the switch.
14. The combination of an upright supporting board, oppositely disposed switches pivotally mounted on opposite sides of said supporting board and comprising yieldably related sections, a contact on said supporting board for each switch adapted to be engaged by one of the sections of the switch, a cam positioned between said switches and arranged to engage the other section of the switch, and means between said switches operable to move one of the switches away from its contact by the movement of the other toward its contact.
15. The combination of an upright supporting panel of insulating material, a pair of switches on each side of said panel pivotally mounted upon and movable toward and from the panel, a fixed contact for each switch mounted on the panel, cam mechanism for simultaneously operating the switches on either side of the panel, a pair of supplemental switches on one side of the panel, and means for operating said supplemental pair of switches whenever the switches on either side of the panel are operated.

Signed by us at Chicago, Illinois.
